corporation of Ohio

Application March 8, 1932. Serial No. 597,560

3 Claims. (Cl. 183—80)

This application relates to improvements in line separators, and in particular relates to desirable modifications of the invention which is described and claimed in my earlier application S. N. 337,597 which matured into Patent No. 1,896,896, Feb. 7, 1933.

The invention relates to the art of centrifugally separating various substances from carrier fluids that are in motion. The work is done by the rotation of the fluid but is accomplished within a so-called separator which is fixed against rotation and contains no rotating parts. Instead the separator includes a so-called whirl promoting tuyère the presence of which causes the vortexial or whirling movement of the fluid as it passes through the body of the separator. Such movement in turn results in the centrifugal separation of the foreign substances or impurities carried by the moving fluid and finally the impurities in one way or another are removed from the path of the fluid before the latter reaches the fluid outlet of the separator.

This present invention has particular reference to improvements in the construction relied upon to accomplish the centrifugal collection of the foreign substances and which permit the same to escape from the separator in advance of its outlet.

High efficiency, high capacity and low original and maintenance costs are all demanded of such separators. They are also required to be efficient throughout a great range of working velocities and to be practical they must be self-cleaning. Such separators are of little greater size than the pipes or carrier conduits wherein they are included and yet are required to be dependable in all respects.

The object of the present invention is to provide a centrifugal separator which shall meet the demands next above recited.

Specifically, the objects of the invention are to provide a separator that shall be adapted for direct inclusion in a carrier line or pipe; that shall oppose little resistance to the passage of the carrier fluid; which shall comprise few parts and all of simple construction; which shall comprise only fixed or stationary parts and none which move or rotate; which shall be effective to remove substantially all centrifugally separable substances from the fluid and to discharge the same from the line; which shall be of relatively small size, weight and cost as compared to separators made by others; which shall be substantially self-cleaning; which shall be durable and strong; which shall be transportable

and installable as a single unit; and, adapted for easy dismemberment. Other objects of the invention will appear hereinafter.

With these objects in view, the invention comprises a centrifugal separator of the construction, 60 combination and arrangement of parts herein-after detailed and exemplified in the drawing that forms part of this specification.

In said drawing Fig. 1 is a longitudinal section of a separator embodying this invention;—Fig. 65 2 is an end view as the device appears when the entrance section of the casing is removed and the bolts being shown in section upon the line 2—2 of Fig. 1;—and, Fig. 3 is a cross section on the line 3—3 of Fig. 1.

On reference to the drawing it will be seen that a separator of the kind embodying this invention is typified by a cylindrical separating chamber 2 having at one end a whirl promoting tuyère 3 and at the other containing a smaller outlet 75 orifice 4.

As represented, the parts forming the tuyère 3, the separating chamber 2 and the outlet 4 are all contained by a generally cylindrical casing having thick walls and adapted for inclusion in 80 a pipe line. The casing of this particular separator is made in two parts. The larger part *a*, is called the body of the separator while the part *b*, is called the inlet bell. Those parts are tightly fastened together by bolts *c*. The ends *a*'' and *b*'' 85 of the casing are shaped and finished for easy inclusion in a carrier pipe of a size which corresponds with the diameters of the openings *a*'' and *b*'' in the ends of the casing.

The whirl promoting tuyère 3 is of the so-called 90 radial type which presents to the entering fluid a circumferential series of inclined deflecting blades 3' and a central hub 3''. By preference the tuyère also presents the so-called vortex defeating cone portion 3a, which latter opens toward 95 the orifice 4 and is coaxial therewith. The construction of the tuyère here shown is described and claimed in my companion application S. N. 597,558, of even date herewith and being clearly shown in Figs. 1 and 2 does not require detailed description in this case. The presence of the tuyère 3 at the intake of the separating chamber 2 causes the passing fluid to whirl within the chamber with a degree of vigor proportioned to the velocity of fluid movement and the angularity of the tuyère blades 3'.

The separating or vortex chamber has a longitudinally extended cylindrical wall 2' and obviously serves to confine the fluid vortex to that diameter while permitting the spiral movement 110

of the fluid toward the orifice 4. As shown, the diameter of the orifice 4 is less than that of the chamber 2 and the whirling movement of the fluid toward and into the orifice is governed by the presence of an annular end or abutment portions 5 and 5a which are interposed between the wall 2' and the margin of the orifice 4. Those surfaces are preceded by narrow eject slots 6, 6a and the centrifugally separated substances which 10 gather upon the wall 2' are urged first toward the abutment 5 by the longitudinal movement of the fluid and are centrifugally discharged through the narrow circumferential slot 6 and then toward the surface 5a at which station residual substances are discharged through the slot 6a. The substances thus discharged through the slots 6, 6a enter large reception chambers 7, 7a.

The chambers 7, 7a are separated by a transverse annular partition a' which partition part is integral with the body portion a. The spaces 7, 7a are provided with respective eject drains 7', 7a'.

Most advantageously, the tuyère 3 is held by the sleeve d, and in accordance with aforesaid application S. N. 597,558 may be a unitary part of the longitudinally extended sleeve d, that contains the separating chamber 2 and bears the internal cylindrical wall 2. The sleeve d has an external shoulder d' which is seated in a recess provided in the end of the casing body a, and both the tuyère 3 and the sleeve, d, are held tightly between the parts of the casing when the clamping bolts, e, are tightened. A key, 8, may be employed to further lock them against rotative movement within the casing.

The perpendicular abutment surface 5 is formed by machine finishing the outer face of the partition a'. The end 2a of the sleeve portion d stops short of that surface 5 and thus the two parts d and a' are made to form or complete the narrow circumferential eject slot 6 leading outward into the surrounding chamber 7.

The central opening 9 within the part a' is coaxial with the chamber 2 but is of less diameter, in order to provide the annular surface 5 for coaction with the separating chamber. By preference the opening 9 is approached by a conical surface 9a that merges with the surface 5. That formation permits the quiet departure of the whirling fluid from the chamber 2. The opening 9 terminates in a finished lip portion 9" which slightly overhangs the chamber 7a.

While the opening 9 is smaller than the chamber it is of larger diameter than the outlet 4 and it will be seen that the latter is contained by a separately insertable part 4a, an outside diameter which permits it to be installed through the chamber 2 and the partition opening 9.

The part 4a bears the annular surface 5a which in this case is preferably of the slightly conical form shown. The outer end of the part 4a is tightly seated in the outlet neck of the casing, a, and obviously the part 4a forms an inner wall which rises within the chamber 7a. However, the part 4a is of less length than the chamber 7a and thus a space remains open between the end 5a and the partition portion a'. That space is the eject slot 6a before identified. The slot 6a deals with fluid which is under slightly less pressure than that which exists at the slot 6 and hence, as here shown, the slot 6a may and indeed should be wider than the slot 6.

The large open spaces 7 and 7a within the separator body are separated only by the ring-

like partitions a' and are of distinct advantages in the casting of the casing in the foundry and with reference to the finishing thereof in the machine shop. They possess the further advantage of providing ample spaces for the reception, the gathering and the temporary holding of centrifugally separated substances, in preparation for the discharge thereof through respective drain openings.

It will be clear that the described separating chamber 2, is formed by the sleeve d and extends from the tuyère 3 to the abutment ring or surface 5, its outlet end being additionally marked by the slot 6. It will also be clear that the sleeve 4a serves to close the space 7a from within except that the parts a' and 4a are separated to form the described slot 6a.

When the separator is in operation the entering fluid first encounters the angularly bladed tuyère 3. Due to direction and deflection by that element the fluid takes on a rapid whirling motion within the chamber 2. In order to escape from the chamber the vortex or whirling body of fluid must pass through the smaller central opening 9 suffering relative contraction in so doing. From that point the fluid moves forward to the orifice 4 and the whirling stream is further reduced in cross section as it passes into that still smaller opening.

The longitudinal and whirling velocities of the fluid result in a maximum fluid pressure at the juncture of the wall 2' and the abutment surface 5; and the foreign substances which are centrifugally collected on the wall 2' and which are urged forward by the whirling fluid, are very positively ejected through the slot 6 and thus deposited in the surrounding space 7. Meantime, lighter substances still carried by the fluid impact the surfaces 5 and 9a and 5a and those substances are positively whirled outward and thus deposited in the space 7a, being centrifugally ejected upon reaching the lip 9" and the slot 6a. The presence of the abutment surface 5a on the end of the sleeve 4a insures and facilitates such separation of the last of the foreign substances, and the fluid which finally escapes through the orifice 4 is found to be very completely purified.

Having thus described my invention I claim as new and desire to secure by Letters-Patent:

1. A separator of the fixed centrifugal type comprising a hollow casing having an inlet at one end and an outlet at the other and intermediate containing a transverse partition dividing the casing into successive eject chambers, and each of the latter terminating in an eject nozzle, in combination with a cylindrical sleeve fixedly positioned longitudinally within said casing and of less diameter than the first of said chambers, a whirl promoting tuyère fixedly positioned at and coaxial with the inlet end of said sleeve, distant from said partition, the outlet end of said sleeve being separated from said partition by a narrow eject slot leading into said first chamber, said outlet of the casing being coaxial with said sleeve but of smaller diameter and marked by a re-entrant sleeve portion that extends toward the outlet side of said partition but which is separated therefrom by a circumferential eject slot that leads into the second of said chambers, and said partition containing a coaxially central opening of a diameter smaller than that of said sleeve and larger than that of said sleeve portion and bevelled toward the latter.

2. A separator of the fixed centrifugal type comprising a hollow casing having an inlet at

one end and an outlet at the other and inter-
mediately containing a transverse partition di-
viding the casing into successive eject chambers,
and each of the latter terminating in an eject
5 nozzle, in combination with a cylindrical sleeve
fixedly positioned longitudinally within said cas-
ing and of less diameter than the first of said
chambers, a whirl promoting tuyère fixedly posi-
tioned at and coaxial with the inlet end of said
10 sleeve, distant from said partition, a vortex de-
feating cone of smaller diameter than said tuyère
and opening toward the outlet thereof, the outlet
end of said sleeve being separated from said par-
tition by a narrow eject slot leading into said first
15 chamber, said outlet of the casing being coaxial
with said sleeve but of smaller diameter and
marked by a re-entrant sleeve portion that ex-
tends toward the outlet side of said partition but
which is separated therefrom by a circumferen-
20 tial eject slot that leads into the second of said
chambers, and said partition containing a co-
axially central opening of a diameter smaller
than that of said sleeve and larger than that of
said sleeve portion and bevelled toward the latter.
25 3. A separator of the fixed centrifugal type

comprising a hollow casing having an inlet at
one end and an outlet at the other and inter-
mediately containing a transverse partition di-
viding the casing into successive eject chambers,
and each of the latter terminating in an eject
80 nozzle, in combination with a cylindrical sleeve
fixedly positioned longitudinally within said cas-
ing and of less diameter than the first of said
chambers, a radially bladed whirl promoting
tuyère fixedly positioned in and coaxial with the
85 inlet end of said sleeve, distant from said par-
tition, the outlet end of said sleeve being sepa-
rated from said partition by a narrow eject slot
leading into said first chamber, said outlet of
the casing being coaxial with said sleeve but of
90 smaller diameter and marked by a re-entrant
sleeve portion that extends toward the outlet side
of said partition but which is separated therefrom
by a circumferential eject slot that leads into the
second of said chambers, and said partition con-
95 taining a coaxially central opening of a diameter
smaller than that of said sleeve and larger than
that of said sleeve portion and bevelled toward the
latter.
